UNITED STATES PATENT OFFICE

172,323

AGRICULTURAL CULTIVATING IMPLEMENT

William E. Vidler, Dallas, Tex., assignor to Dixie Implement Manufacturing Company, Dallas, Tex., a corporation of Texas

Application October 27, 1952, Serial No. 21,992

Term of patent 14 years

(Cl. D35—2)

To all whom it may concern:

Be it known that I, William E. Vidler, a citizen of the United States of America, residing at Dallas, State of Texas, have invented a new, original, and ornamental Design for an Agricultural Cultivating Implement, of which the following is a specification, reference being had to the accompanying drawings, forming a part hereof.

Fig. 1 is a rear elevational view of an agricultural cultivating implement, showing my new design,

Fig. 2 is a plan view of the implement,

Fig. 3 is a perspective view of the implement, and

Fig. 4 is a side elevational view of the implement.

The dominant features of my design reside in the portions shown in full lines.

I claim:

The ornamental design for an agricultural cultivating implement, as shown and described.
